(57) **CLAIM**

An ornamental design for a body of an electric groomer as shown and described.

DESCRIPTION

FIG. 1 is a perspective view of a body of an electric groomer in accordance with the present invention;

FIG. 2 is a front elevational view thereof;

FIG. 3 is a right side view thereof;

FIG. 4 is a left side view thereof; and,

FIG. 5 is a top view thereof.

The broken lines illustrate portions of the body of an electric groomer and form no part of the claimed design.
